UNITED STATES PATENT OFFICE

2,099,733

TUNING APPARATUS FOR RADIO RECEIVERS

Harold D. Gregory, Haddon Heights, N. J., assignor to Radio Corporation of America, New York, N. Y., a corporation of Delaware

Application April 1, 1932, Serial No. 602,548

11 Claims. (Cl. 250—20)

My invention relates to improvements in pre-selection time-controlled tuning apparatus for radio receivers.

One of the objects of my invention is to provide improved apparatus of the character referred to which automatically tunes the radio receiver to a pre-selected station and also adjusts the volume control automatically to a pre-selected position.

Another object is to provide improved apparatus of the character referred to which can be easily and quickly set for a given program without the necessity for adjustment of any parts such as knobs, sliders or the like.

Other objects and advantages will hereinafter appear.

In one embodiment of my invention, tuning and volume control drums are disposed one within the other and supported for rotation independently of each other about a common axis. The adjacent surfaces of the drums are each provided with contact segments separated by a narrow strip of insulating material extending from end to end of the drum and through substantially 360 degrees to form a spiral. The outer drum is geared to the tuning condenser of a radio receiver, and the inner drum is geared to a shaft for adjusting the volume. The drums are driven by separate reversible motors. In setting up the apparatus for a given selected program whereby different stations will be tuned in automatically at the desired time, control pins are inserted between the adjacent contact surfaces of the drums at desired positions around the same, representing twelve hours of the day. Each pin is provided with two contacts, one engaging the surface of the outer drum, the other engaging the surface of the inner drum. These contacts are adjustable longitudinally of the pin to determine the positions to which the control drums are moved by the driving motors.

By means of a switch rotated by the hour shaft of a suitable clock mechanism, and which is closed by mechanical engagement with the various pins, the operating circuits for the motors are completed at times determined by the positions of the pins. Operation of the motors continues until the insulating strips referred to engage the contacts on a particular pin, at which time the control drums are at the desired positions for tuning in the new station and making the new desired volume adjustment. Pins are also provided for shutting off the radio receiver at any desired time, depending upon the position

at which these pins are inserted between the control drums.

A particular embodiment of my invention is shown in the drawings, wherein

Figure 1 is a vertical sectional view, partly diagrammatic, of control apparatus embodying my invention, the section being taken on the line 1—1 in Fig. 3;

Fig. 2 is a plan view, partly in section, partly broken away, and partly diagrammatic, the section being taken on the line 2—2 in Fig. 1;

Fig. 3 is a front elevational view, looking toward the right in Fig. 1;

Fig. 4 is an enlarged sectional view, the section being taken on the line 4—4 in Fig. 1;

Fig. 5 is a sectional view, the section being taken on the line 5—5 in Fig. 4;

Fig. 6 is a plan view of Fig. 5;

Fig. 7 is an enlarged sectional view taken on the line 7—7 in Fig. 1;

Fig. 8 is an enlarged sectional view, taken on the line 8—8 in Fig. 1;

Fig. 9 is a section taken on the line 9—9 in Fig. 8;

Fig. 10 is a section taken on the line 10—10 in Fig. 1;

Figs. 11 and 12 are enlarged sectional views taken on the lines 11—11 and 12—12, respectively, in Fig. 1;

Fig. 13 is an enlarged fragmentary view taken from Fig. 1;

Fig. 14 is a simplified schematic development, partly diagrammatic, of the various parts in Fig. 1, showing the electrical control circuits; and

Fig. 15 is an enlarged section on the line 15—15 in Fig. 3.

With reference to Fig. 1, a tuning control drum 10 and a volume control drum 11 of insulating material are disposed one within the other for rotation about a common axis 12. The drum 10 has a bearing at 13 on the inner drum for rotation with respect thereto. The left-hand end of the drum 10 is supported for free rotary movement by bearing blocks 14 secured to a supporting panel 15. The right-hand end of the inner drum 11 is supported by and has a bearing on a cylindrical bearing block 16. The left-hand end of this drum is supported by and has a bearing on a casing 17 of suitable clock mechanism for driving a hollow hour shaft 18 and a minute shaft 19 extending through the shaft 18. The clock casing 17 is supported by a bracket 20 secured to the panel 15. A reversible motor 21 has a driving connection, through gears 22 and 23, with the tuning drum 10, the gear 23 being fixed

on the latter. Similarly, a reversible motor 24 has a driving connection, through gears 25 and 26, with the volume-control drum 11, the gear 26 being fixed on the latter.

For the purpose of determining the respective positions to which the control drums 10 and 11 are rotated control pins 27, 28, 29 and 30, for example, are inserted through openings 31 in a plate 32 of insulating material fitted in and forming, in effect, a part of the panel 15. As more clearly shown in Figs. 4, 5 and 6, each pin is provided with a contact 33, carried by a spring strip 34 bifurcated at one end to receive a retaining screw 35. The pin 27 is provided with a longitudinal groove 36 for receiving the strip 34 and screw 35, and a communicating opening 37 through which the contact 33 extends. The contact 33 may be adjusted longitudinally of the pin 27 by loosening the screw 35. The permissible range of adjustment is increased by tapping the pin 27 at 38 for the screw 35, whereby the contact assembly can be reversed, as indicated by the dash-line showing, to support the contact 33 for adjustment along the left-hand half of the opening 37. A similar contact 39 is provided for engagement with the inner surface of the tuning drum 10. The drum 10 is provided with contact segments 40 and 41 separated by a narrow spiral strip of insulating material 42. The drum 11, likewise, is provided with contact segments 43 and 44 separated by a narrow spiral strip of insulating material 45.

As more clearly shown in Figs. 11, 12 and 13, a normally closed switch 46 is carried by an arm 47 fixed on the hour shaft 18, and a normally open switch 48 is carried by an arm 49 also fixed on the hour shaft. The contact 50 of the switch 46 is connected as shown to a brush 51 engaging a ring 52. Also, the contact 53 of the switch 48 is connected as shown to a brush 54 engaging a ring 55. The arms 47 and 49 and the rings 52 and 55 are insulated from the shaft 18 by a suitable insulating sleeve 56. Also, the rings 52 and 55 are insulated from the arms 47 and 48, as shown, by suitable insulating rings 57.

The arms 47 and 49 are electrically connected by a suitable connection 58. The disposition of the arm 49 is such that as the same is rotated by the hour shaft, the switch 48 engages a projection 59 with which each of the pins is provided, and is thereby closed.

The field windings 60 and 61 of the motor 21 are connected to the segments 40 and 41, respectively, through the connections 62 and 63, the brushes 64 and 65, the commutator rings 66 and 67, and connections 68 and 69. In like manner, the field windings 70 and 71 of the motor 24 are connected to the segments 43 and 44, respectively, through connections 72 and 73, brushes 74 and 75, commutator rings 76 and 77, and connections 78 and 79.

As shown in Fig. 2, a shaft 80 for manually adjusting the usual tuning condenser gang 81 of a radio receiver, indicated generally by the reference numeral 82, is geared to the tuning drum 10 through a gear 83 meshing with the gear 23. Also, a volume control shaft 84 for manually adjusting a suitable volume control resistance 85, or some other part for controlling the volume, is geared to the volume control drum 11 by the gear 86 meshing with the gear 26. An additional volume control is also provided in the form of a variable resistance 85a, and is manually operable independently of operating action of the control 85.

From this it will be seen that the radio receiver can be manually tuned and adjusted at any time, by turning the usual knobs 81 and 88, independently of and without interfering with the automatic control apparatus.

The reference numeral 89 designates a power supply switch or any other switch effective to place the receiver in condition for operation or non-operation.

The operation of my improved automatic control apparatus will now be explained with reference, more particularly, to Fig. 14. When the hour hand 90 reaches the twelve o'clock position, for example, the switch 48 will be closed by reason of its engagement with the projection 59 on the pin 27. The circuit of a relay winding 91 will then be closed through a resistance 92, a battery 93, a switch 94, a relay switch 110 also closed at this time, as hereinafter explained, connection 95, switch 48 and connection 96. The contacts 97, 98, 99 and 100 will, thereupon, be closed against the biasing action of a spring 101.

The closed contacts 100 short-circuit the switch 89 and place the receiver in operative condition. Since the contact 39 is in engagement with the switch contact 41, the operating circuit of the motor 21 is completed through the connection 63, the field winding 61, the closed contacts 97, the battery 93, the switch 94, the connection 95 including the closed switch 110, the closed switch 48 and the pin 27 back to contact 39. The motor 21, therefore, operates to rotate the tuning drum 10, and the condenser 81 until the insulating strip 42 contacts with the contact 39, at which time the motor circuit is opened. If the relative position of contact 39 and the drum 10 had been such that this contact had been in engagement with the contact 40, the field winding 60 would have been connected in circuit to cause rotation of the motor in the opposite direction until, as before, the insulating strip 42 would engage the contact 39.

The operating circuit for the motor 24 can be traced from contact 33 through the connection 72, the field winding 70, the closed contacts 98, the battery 93, the connection 95 including the closed switch 110, the closed switch 48, and the pin 27 back to the contact 33. The motor 24 will, therefore, operate to drive the volume control drum 11 and the volume control resistance 85 until the contact 33 engages with the insulating strip 45, at which time the motor circuit is opened. If the contact 33 had been in engagement with the switch segment 44, the field winding 71 would have been connected in circuit, in which case the motor would have operated in the reverse direction. The receiver will now be tuned to the new station and the volume control 85 adjusted as desired for this station.

From the foregoing it will be seen that when the switch 48 is closed by engagement with the projection 59 of any control pin, the receiver is set into operation by closure of the switch 89, if it has not previously been operating, and the tuning condenser and the volume control 85 are automatically set for the particular station and volume adjustment called for by the pin, as determined by the positions of the contacts 33 and 39.

The closed contacts 99 operate to maintain the circuit of the relay 91 through the connection 102, the switch 94, the battery 93, the resistance 92, the winding 91, the connection 96, the closed switch 46, and a connection 103. When, therefore, the switch 48 moves out of engagement with

the projection 59, the relay winding 91 remains excited.

If it is desired to shut off the receiver at a pre-determined time, a plug or stop pin 107 is used.

- 5 This plug has a projection 106 which engages the switch 48 to open the holding circuit for the relay winding 91 when the hour hand 90 reaches the position corresponding to that of the plug 107. The spring 101 is then effective to open the various switch contacts and hold the same open until the switch 48 engages another control pin, such, for example, as the pin 28 in Fig. 3.

From the foregoing it will be seen that each pin calls for the tuning in of a particular station, 15 and a predetermined volume adjustment, as determined by the respective longitudinal positions of the contacts 33 and 39. It will also be noted that in using any control pin, the same is inserted through the desired opening 31 and pushed 20 home, with its head 106a engaging the face of the plate 32. For the purpose of holding the control pins in such position, each of the same may be provided with a spring retaining element 106, as shown in Figs. 8 and 9, which engages the edge 25 107a of the opening 31 with a strong snap action.

As shown more clearly in Fig. 7, each of the openings 31 may be provided with recesses 108 for permitting the protruding ends of the contacts 33 and 39 to pass through freely when the 30 pin is inserted through the opening.

In the set-up as shown in Fig. 3, the receiving system will be adjusted automatically for the following program:

At twelve o'clock the receiver starting switch 89 35 is short-circuited and the station WJZ is tuned in by the control pin 27. The receiver is shut off at one o'clock by the stop pin 107. The station WOR is tuned in at three o'clock by the pin 28. The station WLIT is tuned in at five-thirty 40 o'clock by the pin 29. The station WJZ is tuned in at seven o'clock by the pin 30. The receiver is shut off at nine-thirty o'clock by the stop pin 109.

To provide for precision of operation, in the 45 way of the motor circuit being completed exactly on each hour and half hour at which any control pin might be, it is proposed to insert the normally open relay switch 110 in series with the switch 48, and to excite the relay winding 111 exactly on each 50 hour and half hour by any suitable electrical contact mechanism which may be driven in any well known manner by the clock mechanism. The adjustments are such that when the switch 48 engages any pin it is closed before the relay winding 111 is excited, and the exciting circuit for this 55 winding is maintained for a period sufficient to allow for tuning and adjustment to the new station, after which the winding 111 is de-energized while the switch 48 is still closed.

60 From the foregoing it will be seen that in my improved control apparatus the various stations are automatically tuned in and the volume control is simultaneously and automatically adjusted to the desired point for the respective stations, 65 and that in setting up the apparatus for any particular program it is only necessary to insert the control pins through the openings 31 at the desired points, these pins being pushed all the way home. With this arrangement, it is not necessary, as in many of the various control devices proposed heretofore, for the operator to adjust any knobs or other control elements or to insert only certain portions of the control pins in selecting the particular station desired. Furthermore, by 70 adjusting the volume-control resistance 85a, the

volume level can be varied to compensate for pronounced changes in operating conditions, such as might be attributed to seasonal atmospheric changes. For example, if it develops that the volume-control contacts 33 of the various control pins no longer call for the desired degrees of volume due to some pronounced change in the general operating conditions, it is only necessary to vary the auxiliary volume control 85a until the level for this and all other stations is at the desired point. After this one readjustment, no further attention to the control 85a is required until another change in the general operating conditions necessitates another readjustment.

It will be seen, further, that the receiver can 15 be manually adjusted at any time, without interfering in any way with the automatic control apparatus, for which purpose the switch 84 is opened to render the latter ineffective.

The clock mechanism may be of the well known 20 spring driven type, or may comprise a synchronous driving motor.

Although the disclosed embodiment of my invention provides only for automatic adjustment every half-hour, it will be apparent to those skilled 25 in the art that by increasing the size of the drums and the various other parts proportionally, automatic tuning can be effected every quarter hour or less. Also, for this purpose, the control pins 27 may be made flat, and generally rectangular in 30 cross-section, with the contacts 33 and 39 protruding from the opposite narrow edges. With such modifications, my improved apparatus might be made capable of automatically tuning and adjusting the receiver for programs preselected over 35 the period of an entire week, in which case the arms 47 and 49 would be made to rotate at the rate of one revolution a week.

Various other modifications, such as in the shape and arrangement of the parts, may be made 40 without departing from the spirit of the invention or the scope of the claims.

I claim as my invention:

1. In a system of the character described, a 45 radio system having independently operable plural means for controlling the same, means for effecting control operation of each of the control means, and means for governing said second-named means; said governing means including a pair of contact drums supported for rotary movement independently of each other about a common axis, each of said drums provided with electrical contacts, and a member having contacts disposed for engagement with the respective contact surfaces of said drums.

2. In a system of the character described, a 50 radio system having independently operable plural means for controlling the same, means for effecting control operation of each of the control means, and means for governing said second-named means; said governing means including a pair of contact drums supported for rotary movement independently of each other about a common axis and disposed one within and in spaced 55 relation with respect to each other, the outer surface of the inner drum and the inner surface of the outer drum provided with electrical contacts, and control elements insertable between said drums and provided with contacts engageable respectively with said surfaces.

3. In control apparatus for a radio receiver 60 having rotary tuning mechanism and adjustable volume control mechanism, a separate actuating member for each of said mechanisms, means for separately actuating each of said members, and a 65

- plurality of manually and independently adjustable pins, each simultaneously cooperating with both said members to determine the respective ranges of movement of said members by said actuating means.
5. In control apparatus for a radio receiver having rotary tuning mechanism and adjustable volume control mechanism, an actuating member in the form of a drum for each of said mechanisms, means for separately actuating said drums, and a plurality of manually adjustable plugs, each simultaneously cooperating with both said drums to determine the respective ranges of movement of said drums by said actuating means, said plugs forming with said drums part of an operating electrical circuit for said actuating means.
6. In a radio receiving system, rotary tuning means therefor, an electric motor for driving said tuning means, and switch means for controlling the motor circuit, said switch means comprising a drum driven by said motor and individual control pins, each having a contact adjustable along its length, adaptable for placement at different radial positions with respect to said drum and operable independently upon said positions and contact adjustments to determine the controlling action with respect to the motor circuit.
7. In control apparatus for a radio receiving system, adjustable means for tuning said system, means for adjusting said tuning means comprising movable drum structure, an electric motor for driving said drum structure, a plurality of control pins associated with said drum structure for controlling movement thereof, means for supporting said pins at different radial positions with respect to said drum structure, an operating circuit for said motor, switch means forming part of said circuit, a radial arm carrying said switch means into successive engagement with said pins, and a clock mechanism for driving said radial arm.
8. In control apparatus of the character described, two drums supported one within the other in concentric and spaced relation for independent rotation about a common axis, the adjacent faces of said drums provided each with two switch segments insulated from each other and spaced along a spiral at their adjacent edges, means for driving said drums, electrical control circuits for said driving means, and individual control elements insertable into said apparatus between said drums at selected positions around the same and each provided with two contacts engageable respectively with the pairs of switch segments, said control elements and said switch segments forming part of said control circuits.
9. In a radio receiver having independently operable tuning and volume control means, means for effecting control operation of each of the said control means, and means for governing said second named means, said governing means including a pair of contact drums supported for rotary movement independently of each other, each of said drums being provided with electrical contacts, and a plurality of independently adjustable selector keys having contacts disposed for engagement with the respective contact surfaces of said drums.
10. In a radio receiver having independently operable tuning and volume control means, means for effecting control operation of each of the said control means, and means for governing said second named means, said governing means including a pair of contact drums supported for rotary movement independently of each other, each of said drums being provided with electrical contacts, a plurality of independently adjustable selector keys having contacts disposed for engagement with the respective contact surfaces of said drums, and clock actuated mechanism for operating said drums.
11. Automatic time control mechanism for a radio receiver including a control member of said receiver, a tubular member operatively connected with said control member, means to rotate said tubular member to adjust said control member, means defining a plurality of openings circularly arranged about and extending longitudinally of said tubular member, a removable plug adapted to be inserted in one of said openings, adjustable means carried by said plug coacting with the tubular member for determining the direction and amount of rotation of said tubular member, a clock mechanism, and means, driven by said clock mechanism, cooperating with said plug for determining the instant when said tubular member begins to rotate.

HAROLD D. GREGORY.
